United States Patent Office.

STEPHEN V. BARNES, OF WHITNEY'S POINT, NEW YORK, ASSIGNOR
TO HIMSELF AND ISAAC G. DUNDORE, OF SAME PLACE.

Letters Patent No. 92,563, dated July 13, 1869.

IMPROVEMENT IN SIDING-GAUGE.

The Schedule referred to in these Letters Patent and making part of the same.

To all whom it may concern:

Be it known that I, STEPHEN V. BARNES, of Whitney's Point, in Broome county, and State of New York, have invented a new and useful Improvement on Apparatus for Siding Buildings; and I do hereby declare that the following is a full, clear, and exact description of the construction and operation of the same, reference being had to the accompanying drawings, making a part of this specification, in which—

Figure 1 is a perspective view.

Figure 2 represents a section of a building in process of laying the clapboards, showing two of the implements in use.

Similar letters of reference indicate corresponding parts in each figure.

The nature of my invention consists of a graduated bar having two pointed legs, one of which is stationary at the end of said bar; the other is movable, and may be set to any required width or "lap" of siding, and held in position by a thumb-screw. When set, the stationary leg or point may be driven into the board, and the next piece placed upon it and nailed, thereby obviating the ordinary process of gauging with compasses, and holding it in position for nailing with temporary nails driven into the preceding clapboard, and otherwise facilitating the operation.

To enable others to make and use my invention, I will proceed to describe its construction and operation.

I construct the bar A, of my "gauge for setting siding," of steel or other suitable material, and divide it into inches and quarters, or less, if required.

I then provide it with two legs or pointed pieces,

B C, the upper one of which I attach to the end of the bar, and secure it by a rivet. In the other, I cut a slot, and fit it to slide upon said bar, and secure it in position by a thumb-screw, D.

Near the upper end of the bar A, I attach a handle, E, of sufficient size to slip upon the thumb, for the purpose of more conveniently holding one or more of them for use. For ordinary use two of them will be required, as represented by fig. 2.

The lower piece of siding or clapboard is first nailed to its place, when the required "lap" is determined by measurement of the space to be enclosed, the gauge is then set, and the pointed end of the lower leg C placed under the edge of the preceding board F, when the point of the leg B is driven in sufficiently to hold the next piece in position for nailing, thereby greatly facilitating the operation, and insuring more accuracy in lapping and placing the work in position.

I am aware that the several devices herein shown and described, when taken separately, are of themselves not new.

What I claim, is—

The combination of the graduated bar A with a stationary pointed leg B at one extremity, and the movable pointed leg C and set-screw D at the other extremity, and with the bail E between, all as herein shown and described.

STEPHEN V. BARNES.
